UNITED STATES PATENT OFFICE

CALEB S. DE WITT, OF LOCKPORT, ILLINOIS.

WRENCH.

SPECIFICATION forming part of Letters Patent No. 391,588, dated October 23, 1888.

Application filed March 21, 1887. Renewed August 13, 1888. Serial No. 282,641. (No model.)

To all whom it may concern:

Be it known that I, CALEB S. DE WITT, a citizen of the United States of America, residing at Lockport, in the county of Will and

5 State of Illinois, have invented certain new and useful Improvements in Wrenches, of which the following is a specification.

This invention relates to certain improvements in a differential wrench, which is fully 10 set forth and explained in the following specification and claim, reference being had to the accompanying drawings and the letters and figures of reference thereon, which form a part of this specification, in which—

15 Figure 1 is a side view of the wrench complete. Fig. 2 is a central longitudinal section of the wrench-handle and a portion of its inner jaw and sleeved shank, and a side plan view of its outer jaw, its bar, and a portion of the 20 sleeved shank of the inner jaw. Fig. 3 is a side view of the outer section of the handle detached from its inner section. Figs. 4 and 5 are cross-sectional views taken, respectively, on lines 1 and 2 of Fig. 2.

25 Referring to the drawings, B represents the bar of the wrench, which has a heavy screw-thread, S, cut in its end entering the handle, and also has the outer jaw, J', integral with its outer end, as shown in Figs. 2 and 3. J 30 represents the inner jaw of the wrench, having an integral elongated hollow shank, R, and is sleeved on bar B, as shown in the drawings. Shank R extends back into the handle and has a fine screw-thread, E, cut on its extending end, 35 as shown in Figs. 2.

D and D' represent the handle, which is made in two parts and united in such manner that they can be rotated independent from each other. (See Fig. 2.) The inner section, 40 D', of said handle is formed with an annular screw-threaded neck, F, fitted on the screw-threaded end E of shank R, the extreme end of said neck being unthreaded and of sufficient size to project over shank R, beyond said

45 screw-threads E. The remaining portion of said handle-section is chambered for the reception of the fellow handle-section. The outer section, D, of said handle has its forward end, O, offset and reduced in diameter sufficiently to be fitted into the chamber of section D', as shown in Figs. 2 and 3, and has an annular groove, I, formed in said reduced part, into

which the lugs Z are forced, which serve to unite said handle parts and at the same time permit them to rotate independently from each other. 55

S' is an annular screw-threaded section within and integral with said handle-section D, and is fitted on the screw-threaded end of bar B in such manner as to operate said bar 60 when said handle-section is rotated. In the rear of said screw-threaded section said handle-section is chambered for the purpose of giving space for the washer P, which is secured to the end of bar B by means of a screw, said 65 washer being for the purpose of engaging the shoulder of screw-threaded section S' to prevent the bar B from moving out too far, and through the end of handle-section D is an aperture, through which said washer is introduced and secured, and a screw-plug, C, fitted in said aperture, closes it and excludes dirt and dust from the interior of the handle. 70

Referring to Fig. 4, Z' represents lugs, which are formed as a part of handle-section D', and 75 are arranged in such position as to be over channel I of handle-section D. When said parts are together, the said lugs Z' are subjected to pressure sufficiently to force them in the opposite direction into said channel I, thus 80 forming the lugs Z, the metal from which the handle parts are constructed being of such nature to thus bend.

B' represents a portion of bar B, adjacent to jaw J', and is rectangular in cross-section, 85 and is fitted into a corresponding section, R', of shank R, adjacent to jaw J, (see Figs. 2 and 5,) which form of said parts at that place increases strength and prevents rotation of the bar B in shank R. The jaws J and J', as represented, are adapted for use in gripping and turning square objects. If desired, a second pair of toothed jaws arranged opposite jaws J and J', such as is shown at G and G' in Fig. 2, may be used for gripping and turning round 90 objects. 95

In operation the jaw J' of the wrench is adjusted either from or to jaw J by means of rotating handle-section D, (see dotted lines in Fig. 1,) which, by means of its annular screw-threaded section S' turning on the bar-screw S, works bar B out or in, carrying with it jaw J', and, as said screw is of heavy pitch, said adjustment is rapid. After the required ad-

justment is made, as described, and it is de-
sired to get a very tight grip on the object to
which the adjustment was made, the inner
5 handle-section, D', is rotated backward or to
the left, which brings into action the fine screw-
threads E E of shank R, and said handle-section,
which forces jaw J out and closes upon
the object with a very tight grip, (see dotted
10 lines in Fig. 2,) and thus an object may be
gripped and held as firm as when placed in a
vise.

As a means of uniting the two handle-sections D and D', pins or screws may be set
15 through the shell of section D' and entered
into channel I, which would be a mechanical
equivalent for the lugs Z Z', as shown.

To prevent the hands from slipping when
operating the wrench, the two handle-sections
20 are knurled, as shown in Fig. 1, and by the use
of such knurling the wrench is considerably
beautified.

It will be observed, first, that the screw-
threads in this wrench are all within the handle
and not exposed to view or dirt, thus leaving
25 the exterior of the wrench plain, even, and
symmetrical; second, that the larger the ob-
ject the wrench is adjusted to the greater the
leverage gained at the handle, as jaw J' moves
30 from the handle when adjusted out; third,
that the inner jaw, J, is given great strength

by means of the magnitude of its shank R;
and, fourth, by the use of such cylindrical
shank R the neck of the wrench is given great
strength, placed in a neat compact form.
35 The handle-sections are provided with pin-
holes V, as shown, for the insertion of a pin or
lever for rotating said sections to cause the
jaws to more firmly grip the object than can
be done by simply grasping the handle, said
40 pin or lever being shown in dotted lines in
Fig. 2.

Having thus described my invention, what I
claim as new, and desire to secure by Letters
Patent, is as follows, to wit:

The combination of bar B, having the jaw 45
J', and shank R, having the jaw J and re-
spectively provided with the differential ex-
terior screw-threads, S and E, as described, and
the handle-sections D D', rotatably secured
50 together and respectively provided with the
annular differential screw-threads, as set forth,
and adapted to be independently rotated to
adjust said jaws, in the manner substantially
as and for the purpose specified.

CALEB S. DE WITT.
